UNITED STATES PATENT OFFICE

121,507

DESIGN FOR A SALAD MOLD

Nancy Viola Drake, Unionville, Mo.

Application May 24, 1940, Serial No. 92,578

Term of patent 7 years

To all whom it may concern:

Be it known that I, Nancy Viola Drake, a citizen of the United States, residing at Unionville, in the county of Putnam and State of Missouri, have invented a new, original, and ornamental Design for a Salad Mold, of which the following is a specification, reference being had therein to the accompanying drawing, forming part thereof, in which

I claim:

The ornamental design for a salad mold, as shown.

NANCY VIOLA DRAKE.
